ORREN A. SAWYER, OF LOWELL, MASSACHUSETTS, ASSIGNOR, BY MESNE ASSIGNMENTS, TO THISSELL COMPANY, OF PORTLAND, MAINE, A CORPORATION OF MAINE.

SHUTTLE OR FILLING-CARRIER FOR LOOMS.

1,076,393.

Specification of Letters Patent.

Patented Oct. 21, 1913.

Application filed October 25, 1909. Serial No. 524,331.

To all whom it may concern:

Be it known that I, ORREN A. SAWYER, a citizen of the United States, residing at Lowell, in the county of Middlesex and 5 Commonwealth of Massachusetts, have invented a certain new and useful Improvement in Shuttles or Filling-Carriers for Looms, of which the following is a specification.

10 This invention relates to shuttle or filling carriers for looms and its object is to provide means for producing a substantially increased tension on the filling just before the exhaustion of said filling.

15 In a previous application, No. 477,504, filed February 13, 1909, I have shown a device arranged in a shuttle-chamber near the pivoted end of the spindle to create a friction upon the filling wound upon the bobbin 20 or cop-tube, in such a manner as to retard the unwinding of said filling just before the exhaustion of the filling and I have shown in said application pieces of cloth and brushes secured in the shuttle-body in such 25 a manner as to create such friction and tension. The present invention serves the same purpose as said cloth or brushes and will be used to operate controlling means for stop-motion devices or weft-replenishing devices as stated in said previous application. 30

In this application I have shown as a tension-producing means a spring, as of metal, adapted to press upon the filling first wound upon and last unwound from the bobbin or 35 cop-tube, to increase the tension of the filling just before the exhaustion of the filling. The pressure of such a spring is more capable of exact regulation and is less subject to be affected injuriously by wear and such a 40 spring can be more readily attached and detached from the shuttle-body if necessary than the devices for a like purpose shown in said previous application. I have also provided in a novel and improved manner, for 45 causing the tension-producing means to act in connection with the last few pick-lengths upon the filling-holder in producing the increased tension of the yarn.

In the accompanying drawing on three 50 sheets, the first three figures show a leaf-spring or spring formed of sheet material, Figure 1 being a plan of the bottom of a shuttle provided with such a spring; Fig. 2, a side elevation of an inverted shuttle 55 partly in section with such a spring; Fig.

3, a plan of the bobbin-retaining catch and said spring. In the other figures the spring is shown in the form of a wire. Fig. 4 is a plan of a bottom of a shuttle provided with a wire spring; Fig. 5, a side elevation of an inverted shuttle partly in section to show the tension spring in side elevation; Fig. 6, a plan of the shuttle, bobbin and spring, the bobbin being broken away above the middle of the spring. Figs. 7, 8 and 9 show the 65 wire spring applied to the filling on a cop-tube, instead of a bobbin. With this exception Fig. 7 is similar to Fig. 6 and Fig. 8 like Fig. 5; Fig. 9 being a vertical cross-section on the line 9-9 in Fig. 8. 70

A indicates the shuttle-body; B, a spindle, pivoted at b and held in operative position by a spring C; D, a bobbin; E, a cop or mass of filling wound on the bobbin, as shown in Figs. 1-6;—all of these parts being of the 75 usual construction and operation, except as hereinafter specified.

The head of the bobbin is provided with an annular groove d, into which groove the 80 yarn is wound to form a ring or bunch e of filling before forming the cop E upon the body d¹ or barrel of the bobbin, the yarn passing diagonally over the ungrooved part d² of the bobbin-head from the last wind or turn of yarn in the bunch to the first turn 85 of the cop.

A tension spring which in Figs. 1-3 is represented as a leaf-spring F is rigidly secured to the shuttle-body in such a manner that the free end of said spring bears upon the uncovered space between the bunch e and the cop E so that when the cop has been wholly unwound and the yarn is being drawn from the bunch, said yarn in unwinding will pass under the free end of said 90 spring F, said free end having integral therewith an arc-shaped extension f substantially concentric with the uncovered part of the bobbin between the cop proper and the bunch and pressing upon said uncovered 95 space with sufficient force to create an extra or abnormal tension upon the yarn as it passes under the arc f. Either or both ends of the arc f are turned outward or away 100 from the center of said arc to allow the yarn to enter between said arc and the bobbin, as shown at f².

In Figs. 1-3 the spring F is represented as secured to the shuttle-body by the same screw g which holds the bobbin retaining 110

check G (of usual construction) in place and the body of the spring F is shaped to fit the slot α which receives said check G.

The bunch e should contain enough yarn 5 to make two or more courses of filling in the cloth being woven.

The tension device above described is intended to be used with suitable means for stopping the loom or for replenishing the 10 filling before the filling is entirely exhausted, and may be used for the first of these purposes with the devices shown and described in my application for Patent No. 477,503, filed February 13, 1909, and for the other of 15 these purposes with the invention which is the subject of another application No. 477,502, filed February 13, 1909, by me.

In Figs. 4-6, I have shown a different form of spring F¹ formed of wire, the middle portion of which is bent into an arc f¹ adapted to fit and press upon the uncovered space between the cop and the bunch for the purpose above described with regard to the spring F. From the arc the wire rises vertically on each side of the bobbin and spindle and near the top of the shuttle-body at f³ on each side of the bobbin is bent backward and near its extreme ends is formed into loops or eyes at f⁵ through which screws f⁷ are driven 30 to secure said spring F¹ to the shuttle-body, said eyes and the adjacent end portions of said spring being let into depressions α^2 below the top of the shuttle, to avoid any danger of these parts of the spring catching 35 on the warp-threads.

Except as described the parts shown in Figs. 4-6 are like those shown in Figs. 1-3 marked by the same letters of reference.

In Figs. 7-9 a cop-tube D¹ is substituted 40 for the bobbin shown in the figures already described and the arc-shaped middle portion of the spring F² has a narrower arc f⁴ to afford a suitable bearing on the cop-tube which is usually much smaller in diameter

than the head or barrel of a bobbin. In 45 other respects the parts represented in Figs. 7-9 have already been described and are designated by the corresponding letters of reference, the bunch e being wound on the tube and not in a groove thereof. 50

I do not limit myself in all cases to separating the ring or bunch of yarn at the base of the cop from said base by an uncovered space, because in some embodiments of the invention the ring or bunch may be continuous with said base and the uncovered space be omitted. 55

I claim as my invention:—

1. The combination in a filling-carrier of a shuttle-body, a filling-holder, means for 60 supporting said holder in said body and a spring for producing a substantially increased tension on the filling just before the exhaustion of said filling from said holder.

2. The combination in a filling-carrier, of 65 a shuttle-body, a filling-holder, means for supporting said holder in said body and a metallic spring for producing a substantially increased tension on the filling just before the exhaustion of said filling from said 70 holder.

3. The combination in a filling-carrier, of 75 a shuttle-body, a filling-holder adapted to carry a ring or bunch of yarn and a cop of yarn separated by an uncovered space and a spring supported by said shuttle-body and arranged to press upon said uncovered space to create a tension upon yarn being unwound from said bunch after the unwinding of said cop. 80

In witness whereof, I have hereunto affixed my signature in the presence of two witnesses.

ORREN A. SAWYER.

Witnesses:

ALBERT M. MOORE,
GRACE CROWLEY.
